His Attorney.

UNITED STATES PATENT OFFICE.

WILFRED BARNES, OF FOREST PARK, ILLINOIS, ASSIGNOR TO EDISON ELECTRIC APPLIANCE COMPANY, INC., OF CHICAGO, ILLINOIS, A CORPORATION OF NEW YORK.

DESIGN FOR A COMBINED ELECTRIC HEATER CASING AND STANDARD.

Application filed July 25, 1924. Serial No. 10,261. Term of patent 14 years.

To all whom it may concern:

Be it known that I, WILFRED BARNES, a citizen of the United States, residing at Forest Park, in the county of Cook, State of Illinois, have invented a new, original, and ornamental Design for Combined Electric Heater Casing and Standard, of which the following is a specification, reference being had to the accompanying drawing, forming a part thereof.

In the accompanying drawing Fig. 1 shows a front elevation view of a combined

electric heater casing and standard embodying my new design; while Fig. 2 shows a side elevation view thereof on a reduced scale.

I claim:

The ornamental design for a combined electric heater casing and standard substantially as shown.

In witness whereof, I have hereunto set my hand this 19th day of July, 1924.

WILFRED BARNES.
